UNITED STATES PATENT OFFICE.

SAMUEL ALFRED TAYLOR, OF WILKINSBURG, PENNSYLVANIA.

MECHANISM FOR HANDLING CARS.

1,193,630.

Specification of Letters Patent. Patented Aug. 8, 1916.

Application filed January 29, 1907. Serial No. 354,690.

To all whom it may concern:

Be it known that I, SAMUEL ALFRED TAYLOR, a citizen of the United States, residing at Wilkinsburg, in the county of Allegheny and State of Pennsylvania, have invented a new and useful Improvement in Mechanism for Handling Cars, of which improvement the following is a specification.

The present invention relates to an improved apparatus for dumping coal cars, the primary object being the provision of novel means whereby the contents of the car are discharged in a comparatively progressive stream of constantly varying volume, whereby when the coal falls upon a screen there will be sufficient agitation to insure the complete removal of all of the slack.

With this and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a side elevation of a coal tipple constructed in accordance with the invention, portions being broken away and shown in section, and the car being shown by full lines in a tilted position and by dotted lines in an upright position. Fig. 2 is a transverse sectional view through the device, showing the swinging track section which is arranged in advance of the tilting platform. Fig. 3 is an enlarged detail view of the ratchet mechanism and cylinder which are arranged under the tilting track section, portions being broken away and shown in section. Fig. 4 is an enlarged side elevation showing the pawl and ratchet mechanism as well as the rack and pinion arrangement. Fig. 5 is an enlarged side elevation of the main controlling lever. Fig. 6 is a view showing a modified form of my device as utilized for shifting cars, and Fig. 7 is a plan view of the same.

Corresponding and like parts are referred to in the following description and indicated in all the views of the drawings by the same reference characters.

Referring to the drawings, the numeral 1 designates a trestle upon which stringers 2 are mounted, the said stringers forming a

support for the track rails 3. A car 4 of any conventional construction is mounted to travel upon the track, and the said track is formed with a tilting portion 15, and 60 also with a tilting table 6 upon which the car is pushed prior to discharging the contents thereof. The lower face of the tilting table 6 is provided with a plate 7 having a socket 8 formed therein, the said socket receiving a spherical or rounded enlargement 9 at the upper end of a piston 10 which is mounted within an upright cylinder 11. The piston 10 may be provided with a hinged joint 10^a so that the upper end thereof can 70 swing laterally in the necessary manner as the tilting table 6 swings up and down. This cylinder 11 is connected by a pipe 13 to a second upright cylinder 12 located under the tilting track section 15, the said cylinders and pipe being filled with some fluid such as water so that when the piston in one cylinder is moved downwardly, the piston in the opposite cylinder will be moved upwardly.

It may here be noted that the cylinder 12 is shown as having a larger diameter than the cylinder 11 so that a comparatively small movement of the piston therein will produce the necessary movement of the piston 85 10 of the cylinder 11. The piston 14 which is mounted within the cylinder 12 has an operative connection with the swinging end of the tilting track section 15, and is provided upon one side thereof with a rack 16 90 meshing with a toothed wheel 17 rigid with a horizontal shaft 18 which is disposed transversely with respect to the track and is journaled within brackets 19 projecting from the post 20. A ratchet wheel 30 is also 95 rigidly mounted upon the shaft 18, the teeth thereof being engaged by a pawl 31 upon a ratchet lever 23 which is loose upon the shaft. The teeth of the ratchet wheel 30 are inclined in such a direction as to slip 100 easily past the pawl 31 when the shaft 18 is rotated by the downward movement of the piston 14, although they engage the said pawl to prevent the upward movement of the said piston.

The end of the ratchet lever 23 is connected by a rod 21 to the lower end of a main lever 22 which is shown as located adjacent the tilting table 6. This main lever 22 is pivotally mounted at an intermediate 110 point in its length upon a frame 24, and is provided with some conventional form of

latch 25 for engagement with a segmental rack 26 formed in connection with the said frame 24.

In the operation of the device, a loaded 5 car moving along the track 3 is first brought upon the tilting track section 15 so as to depress the same. The piston 14 which is connected to the swinging end of the tilting track section 15 is thereby depressed so 10 as to force the fluid from the cylinder 12 to the cylinder 11 and move the piston 10 upwardly so as to bring the tilting table 6 into an elevated and normal position. As has been previously explained, upon the 15 downward movement of the piston 14 the teeth of the ratchet wheel 30 pass freely under the pawl 31 of the ratchet lever 23. The car is then moved forward upon the tilting table 6, until the wheels thereof are 20 brought into engagement with suitable abutments 5, the said table 6 being locked against tilting by means of the ratchet wheel 30 which is held against backward movement by means of the pawl 31 of the 25 ratchet lever 23. The operator now grasps the main lever 22 and releasing the latch 25 moves the said lever rearwardly one notch at a time, the said lever 22 being thereby given a jerky movement. This jerky movement of the main lever is imparted to the ratchet lever 21 so as to permit a corresponding backward movement of the ratchet wheel 30 and upward movement of the piston 14. 30 This operation is performed so that the piston 14 is permitted to rise by a quick succession of short movements, and it will be readily apparent that the piston 10 will drop in a corresponding manner. As this piston 10 drops, the table 6 will be tilted so as to 35 discharge the contents of the car upon a screen (not shown, but which may be located in the usual position with relation to the car being unloaded). This tilting of the table in the quick succession of jerky 40 movements will jolt the car so that the contents thereof will be agitated and discharged in a stream of varying volume such as will permit of the coal being effectively screened. This operation is repeated, the lever and 45 ratchet mechanism being reset either by hand or in any other suitable manner.

In Figs. 6 and 7 is shown a modified form of the invention adapted for the shunting or shifting of mine cars, the said device 55 being shown as applied to a coal mine and the cages used therein. A is a track located in the mine, B is the car, while C is a cage adapted to convey the car from the mine to the tracks D at the top of the shaft E. The 60 said tracks A and D are provided with hinged sections F and G, the free ends of which rest respectively upon the pistons H and I operating in the cylinders K and L, the said cylinders being connected by a 65 pipe M. In Fig. 6, the cage in the mine

contains a loaded car which after being carried to the surface is caused to travel to the right until it is brought upon the hinged section G which is normally held elevated by the piston I. The weight of this car causes 70 said piston I to be forced down into its cylinder so as to force fluid into the opposite cylinder K and raise the piston H mounted therein. The hinged section F is thereby elevated so that an empty car thereon will roll down the same and be brought upon the cage preparatory to being again lowered into the mine. The loaded car is pushed off section G, unloaded, and brought around a circular or other suitably shaped 75 track to the hinged section F, and the operation repeated. 80

Having thus described the invention, what I claim as new and desire to secure by Letters Patent, is:—

1. In coal car dumping mechanism, a trestle, a track supported thereon, the said track having at the end thereof a tilting table, and a short distance to the rear thereof a hinged section in combination with a 90 pair of communicating cylinders adapted to contain a fluid, the respective pistons of said cylinders being connected to the tilting table and the hinged section respectively, and means to enable the piston connected to the 95 tilting table to descend in its cylinder by successive drops.

2. In a coal car dumping mechanism, the combination of a trestle or track supported thereon, a tilting table at the end of said track having means to arrest the forward movement of the car, a hinged section a short distance to the rear of said tilting table, a pair of communicating cylinders adapted to contain a fluid, pistons operable 100 in said cylinders and connected to the tilting table and the hinged section respectively and adapted to be operated by the weight of the car acting on and compressing the fluid in said cylinder. 105

3. In a car dumping mechanism, the combination of a track, a tilting table at the end of said track, a hinged section in said track a short distance to the rear of said tilting table, a plurality of communicating cylinders adapted to contain fluid, having pistons operable therein, the said pistons being connected to the tilting table and the hinged section, respectively, a car adapted when on the said hinged section to move the piston 110 connected therewith downward and thereby compress the fluid in said cylinders, and force the piston connected to the tilting table upward; and when on the tilting table to reverse the movement of the pistons, and means to cause the piston connected to the tilting table to drop at successive intervals whereby the car on said table is tilted and the contents discharged in a regulated stream. 115

4. In a car-dumping mechanism, the combination of a track, a tilting table at the end of said track, a hinged section located in said track a short distance to the rear of said tilting table, two communicating cylinders having pistons operable therein, the piston of one of said cylinders being connected to said hinged section, and having teeth or serrations in one side thereof and the piston of the other cylinder being connected to the tilting table, a pawl and ratchet mechanism adapted to control the movement of the piston connected to the hinged section, and a car adapted to actuate automatically the pistons of said cylinders, substantially as described.
5. A car dumping device including a track, supporting means for the track, a tilting table at one end of the track, man-
- ually controlled means for imparting a step 20 by step movement to the tilting table as it is tilted to dump a car thereon, a hinged section interposed in the length of the track, two communicating cylinders, and pistons operable within the cylinders, one of the 25 pistons having an operative connection with the hinged section while the other piston has an operative connection with the tilting table whereby the hinged section will operate as a car passes over the same to return 30 the tilting table to normal position.

In testimony whereof, I have hereunto signed my name in the presence of two subscribing witnesses.

SAMUEL ALFRED TAYLOR.
